(57) **CLAIM**

I claim the ornamental design for an apparatus for securing a workpiece, as shown and described.

DESCRIPTION

FIG. 1 is a perspective view of an apparatus for securing a workpiece according to my new design, the broken lines of the apparatus for securing a workpiece are for illustrative purposes only and form no part of the claimed design;
 FIG. 2 is an additional perspective view of the apparatus for securing a workpiece of FIG. 1, the broken lines of the apparatus for securing a workpiece are for illustrative purposes only and form no part of the claimed design;
 FIG. 3 is a front elevational view of the apparatus for securing a workpiece of FIG. 1, the broken lines of the apparatus for securing a workpiece are for illustrative purposes only and form no part of the claimed design, the rear elevational view being the mirror image thereof;
 FIG. 4 is a plan view of the apparatus for securing a workpiece of FIG. 1, the broken lines of the apparatus for securing a workpiece are for illustrative purposes only and form no part of the claimed design.

FIG. 5 is a bottom view of the apparatus for securing a workpiece of FIG. 1;

FIG. 6 is a right-side elevational view of the apparatus for securing a workpiece of FIG. 1; and,

FIG. 7 is a left-side elevational view of the apparatus for securing a workpiece of FIG. 1.
